UNITED STATES PATENT OFFICE.

WILLIAM B. COGGER, OF CLEVELAND, OHIO, ASSIGNOR TO THEODOR KUNDTZ, OF LAKEWOOD, OHIO.

SUPPORT FOR SWINGING SEATS.

1,050,518.

Specification of Letters Patent.

Patented Jan. 14, 1913.

Application filed October 12, 1910. Serial No. 586,690.

To all whom it may concern:

Be it known that I, WILLIAM B. COGGER, a citizen of the United States of America, residing at Cleveland, in the county of 5 Cuyahoga and State of Ohio, have invented certain new and useful Improvements in Supports for Swinging Seats; and I hereby declare the following to be a full, clear, and exact description of the invention, such as 10 will enable others skilled in the art to which it pertains to make and use the same.

This invention relates to improvements in supports for swinging seats.

The primary object of this invention is to 15 provide a support of the character indicated which is exceedingly simple and durable in construction and not liable to get out of order.

With these objects in view, this invention 20 consists in certain structural features and combinations and arrangement of parts, hereinafter described, pointed out in the claim, and illustrated in the accompanying drawings.

In the said drawings, Figure 1 is a side view of a support embodying my invention. Fig. 2 is a vertical section on line 2—2, Fig. 1, looking in the direction indicated by the arrow. Fig. 3 is a vertical section on line 3—3, Fig. 2, looking in the direction indicated by the arrow. Fig. 4 is a section on line 4—4, Fig. 1, looking in the direction indicated by the arrow. Fig. 5 is an elevation of the flanged side of a portion of the 35 stationary bracket of my improved support. Fig. 6 is an elevation of the roller-bearing side of a portion of the swinging section of my improved support. Figs. 4, 5 and 6 are drawn on a larger scale than Figs. 1, 2 and 3.

Referring to the drawings, A indicates a 40 stationary cast metal bracket which is provided at one side with a laterally facing segmentally spherical integral lug *a* which forms a bearing as will hereinafter appear, and the said bracket is also provided at the 45 said side with an annular flange 10 which extends circumferentially of the said lug or bearing. The flange 10 has an inwardly 50 facing surface 12 which extends circumferentially of the upper portion of the lug or bearing *a*. The flange 10 also has two inwardly 55 facing surfaces 13 and 13 which extend circumferentially of the lug or bearing *a* and in the direction of and gradually ap-

proach the said lug or bearing from and beyond opposite ends respectively of the aforesaid surface 12. The surfaces 12 and 13 are suitably spaced from end to end thereof from the lug or bearing *a*.

To render the construction simple and durable the bracket A is composed of a single casting, and the lug *a* is a member of the said casting.

B represents the swinging section of my 60 improved support. The said section B is instrumental in supporting a seat (not shown) and overlaps the flanged side of the bracket A. The said section B is rotatably mounted on the lug or bearing *a* of the bracket A and arranged to swing in a vertical plane on the said lug or bearing, and preferably the said section B is provided at its bracket-facing side with a segmentally 65 spherical cavity *b* which is engaged by the 70 said lug or bearing.

The swinging section B is provided at its bracket-facing and cavitated side with an integral lug 15 which projects laterally of the 75 said side of the said section and has such arrangement relative to the axis of the said section that the said lug is arranged above the said axis in any position of the said section. The lug 15 is provided with a seat 16 for a loose roller D, which seat is formed in 80 the said lug and extends circumferentially of the lower portion of the roller and thereby prevents lateral displacement of the roller. The seat 16 is obviously arranged above the axis of the swinging section B in 85 any position of the said section. The roller D, thus seated in the said lug 15, is substantially parallel with the axis of the swinging section B.

The surface 12 of the flange 10 is arranged to prevent displacement of the roller D from the seat 16 during the swinging of the rotary section B from the one to the other of its extreme positions but spaced far enough from the lug or bearing *a* to prevent 90 the said surface clamping or bearing against the roller during the said actuation of the said section, but the surfaces 13 and 13 of the aforesaid flange are arranged to frictionally engage the roller during the swinging 95 of the said section in opposite directions respectively and preferably have such arrangement relative to the roller that the one or the other of the last-mentioned surfaces 100 clamps the roller against the seat 16 accord- 105 110

ing as the swinging section B has been swung into the one or the other of its extreme positions. In solid lines, Fig. 3, the swinging section B is shown in one of its 5 extreme positions, and in dotted lines in this figure the said section is shown in its other extreme position. I would here remark that the swinging section B, to render it simple and durable, is composed of a 10 single casting, and that the lug 15 is a member of the said casting.

The roller D extends at one end into close proximity to the bracket and at its other end into close proximity to the swinging 15 section is beveled circumferentially at its ends, as at d, to render the castings composing the bracket A and the swinging section B suitable for the use of the roller without any milling or machining of the 20 said castings at the ends of the roller. The roller D, having a large wearing surface, will not groove the surfaces 13 of the flange 10 of the bracket A during the movements of the swinging section B.

25 Means for preventing displacement of the swinging section B laterally from the bracket A are provided and comprise a bolt E and a nut e (see Figs. 1 and 2). The bolt E is arranged a suitable distance below and 30 parallel with the axis of the swinging section B. The bolt E has its head arranged at the outer side of the bracket A and has its shank extending loosely through a bolt-hole 17 which is formed in and extends 35 laterally through the said bracket below the lug or bearing a. The shank of the bolt E extends laterally through a slot 18 formed in the swinging section B, which slot extends circumferentially of and is arranged 40 concentrically relative to the axis of the said section, and the said slot is long enough to accommodate the location of the bolt during the swinging of the said section.

The shank of the bolt E extends not only 45 through but a suitable distance beyond the outer side of the swinging section B, and the nut e is screwed onto the said shank at and spaced from the said side of the said section, and a washer G is interposed between the said nut and the said section.

The washer G is provided with a lug g which engages the swinging section B at a

point substantially coincident with the axis of the said section. The washer G has an arm 20 which projects under the swinging section B and bracket A and is provided in its free end with a recess 21 engaged by a lug 22 formed on the said bracket. It will be observed therefore that the bracket A and swinging section B are held properly 60 assembled without interfering with the movement of the swinging section.

What I claim is:—

In a support for a swinging seat, the combination, with a stationary cast metal 65 bracket provided at one side with a laterally facing segmentally spherical bearing and a flange extending circumferentially of said bearing, which flange has an inwardly facing surface extending circumferentially of 70 the upper portion of said bearing, said flange also having two inwardly facing surfaces which extend circumferentially of and toward said bearing from and beyond opposite ends of the first-mentioned surface, 75 and a swinging cast metal section rotatably mounted on said bearing and arranged to swing in a vertical plane, said swinging section facing the bracket and provided at its bracket-facing side with a lug, of a loose 80 roller seated in said lug, which roller is substantially parallel with the axis of the swinging section and beveled circumferentially at its ends and extends at one end into close proximity to the swinging section and 85 at its other end into close proximity to the bracket, said roller being clamped to said lug by the one or the other of the aforesaid second-mentioned surfaces according as the swinging section has been swung into the 90 one or the other of its extreme positions, the first-mentioned surface of the aforesaid flange being spaced far enough from the aforesaid bearing to prevent clamping of the roller by said surface during the movement of the swinging section.

In testimony whereof, I sign the foregoing specification, in the presence of two witnesses.

WILLIAM B. COGGER.
